UNITED STATES PATENT OFFICE.

LOUIS M. POTTS, OF TENAFLY, NEW JERSEY, ASSIGNOR TO WESTERN ELECTRIC COMPANY, INCORPORATED, OF NEW YORK, N. Y., A CORPORATION OF NEW YORK.

TROUBLE-INDICATING SYSTEM.

Application filed November 25, 1924, Serial No. 752,080. Renewed January 3, 1927.

This invention relates to telephone exchange systems and more particularly it pertains to recording apparatus especially adapted to telephone exchange systems employing automatic switching apparatus for establishment of conversational connections.

In establishing conversational connections automatically, the apparatus employed for this purpose oftentimes encounters trouble which not only delays the establishment of the desired connection, but also not infrequently requires the close inspection of all apparatus involved in a certain connection in order to determine the cause and source of the trouble. In the case of the coordinate machine switching system these difficulties are even more complex for in such systems a large number of devices performing the same functions are employed, only one for each purpose, however, being selected for the establishment of a connection between a calling and a called party. It has been found, therefore, that the service rendered by such equipment may be materially enhanced by providing apparatus responsive in case trouble is encountered for indicating and recording information concerning the particular apparatus involved in establishing a connection and the point of progress made by the call when trouble occurred. The principal object of the invention is to record information in a simple, efficient and reliable manner immediately when trouble is encountered in the establishment of a conversational connection concerning the apparatus involved in the connection and the point to which the call progressed when trouble occurred.

A feature of the invention relates to a recording mechanism which is adapted to be operatively associated with the switching mechanism when any part of the mechanism encounters trouble and which responds in accordance with the mechanism involved in a connection for recording in different columnar spaces symbols designating the particular apparatus employed in attempting to establish the connection and the point of progress made by the call when trouble was encountered.

This invention is in the nature of an improvement on the system shown and described in patent to W. W. Carpenter No.

1,594,003, issued July 27, 1926, and a general reference is hereby made to that application for an understanding of the manner in which the mechanisms of the present system are arranged, and the details of operation whenever such arrangements and details are hereinafter mentioned but are not particularly illustrated or described.

For the purpose of this case it has been considered sufficient to show only such part of the apparatus or mechanism as is necessary for a clear understanding of the present invention and to confine the detailed description to apparatus involved in the recording of information from which the nature and source of the trouble can be easily ascertained in accordance with the invention.

Referring now to the drawings, Figs. 1 and 2 when taken together end for end with Fig. 2 arranged on the right of Fig. 1 shows the general location of the apparatus for a complete system to which the invention is particularly adapted. Figs. 3 to 6, when arranged in the manner illustrated in Fig. 8 disclose circuits and apparatus involved in indicating and recording the nature and source of trouble. Fig. 3 shows the time measuring mechanism for controlling the operation of the relays of the marker. Fig. 4 illustrates a connector for connecting the control relays of the indicating mechanism to the markers. Fig. 5 shows a part of the trouble indicator. Fig. 6 illustrates diagrammatically the circuits and apparatus for the recording printer. Fig. 7 shows a sample of the record produced when the apparatus encountered several different kinds of trouble.

General description of the system and apparatus.

Referring now for the moment to Figs. 1 and 2, descriptions will be given of the general plan of the system. The lines 100 enter the office and terminate in a number of line switches, such as switch 101. Outgoing from these switches are a number of trunks 100 which extends to district selector switches. For certain reasons it is desirable that the district selector switches be divided into a number of groups, two of which groups 106 and 107 are illustrative. The group 106 comprises a number of district selector

switches, two of which 108 and 109, are shown and trunks such as trunks 104 and 105 leading from the line switches are distributed among these district selector switches. In like manner the trunks 102 and 103 extend to the district selector switches 110 and 111 of the second group 107. It is, of course, obvious that other similar groups may be provided.

10 The trunks outgoing from the district selector switches lead in different directions. For example, some of the trunks 123 and 125 extend to office selector switches. The office selector switches may be arranged in groups 15 similar to the district selector switches, the selector 127 being of one group and the selector 128 being of a second group of office selectors. The trunks 132 leading from the office selectors extend to distant offices to 20 take care of interoffice communications.

Other trunks leading from the district selector switches, such as the trunks 122 and 124, extend to incoming switches located in the same central office.

25 These incoming switches are similarly divided into two groups, group 200 comprising switches 202 and 203 and the group 201 comprising the switches 204 and 205. The trunks outgoing from the incoming switches, 30 such as trunks 212 and 213 lead to the various connector switches of the several groups. Only one group of connector switches 214, which includes the switches 35 215 and 216, is illustrated in the drawing. The connector switches have access to the called lines as 217 and 218.

The trunks which lead from the line switch to the district selectors also appear in the sender selector switches 112, which 40 operate to extend these trunks to the register senders. Two of these senders 113 and 114 are shown. The sender connector may comprise a plurality of sections 115, 116, etc. which serve to connect the senders to the 45 outgoing markers 117 and 118. While only two of the markers are illustrated any suitable number may be provided for handling the required traffic.

In order to connect the markers to the 50 district frames there are provided a number of frame connectors, one for each group of district selector frames. Frame connector 119, for instance, serves to connect any of the markers to any of the frames in the selective group 106, while frame connector 120 serves to connect any of the markers to any of the frames in the district selector group 107.

The outgoing markers are connected to the trunks outgoing from the district selector switches by means of district trunk connectors 121 and 133, etc.

Likewise, frame connectors 129 and 130 are provided for associating the outgoing markers, respectively, with the office selector switches of the two corresponding groups,

while trunk connectors such as the trunk connector 131 are provided for associating the outgoing markers with the two groups of trunks leading from the office selector switches.

70 A sender connector device which may comprise a plurality of sections 208 and 209 serves to connect the senders with any one of a plurality of incoming markers, two of which, 210 and 211, are shown. These 75 incoming markers are associative with frame connectors 206 and 207, respectively, with the groups of incoming selector frames 200 and 201.

80 A number of final translators 219 and 220 are provided. There may be any number of these translators depending on the number of called subscribers' lines, there being one pertaining exclusively to a different portion of the subscribers' lines. Any of the 85 final translators may be associated with the incoming markers.

85 The final translator 219, for example, is arranged to make connection with any of the final connector switches of the group 214 and serves to control any of these switches to make a connection to the called subscribers' lines. In a similar manner the final translator 220 is associative with the connector switches of a different group and governs the same to extend connections to other called subscribers' lines.

90 A trouble indicator 150 is provided in common to all outgoing markers 117 and 118, etc. and may be associated with any of the markers in case of trouble. Connectable with the trouble indicator 150 is recorder 151, which responds to the operation of the trouble indicator 150 to record the information given by the trouble indicator to provide a permanent record of the nature and source of the trouble. Similarly, a trouble indicator 250 is provided for the incoming markers 210 and 211. Likewise, a recorder 105 251 is associative with the trouble indicator 250 for recording the nature and source of trouble encountered through the operation of the incoming markers 210 and 211, in a manner similar to that described in connection with the trouble indicator 150. 110

115 Referring now to Figs. 1 and 2 a more detailed explanation will be given of the general arrangement of the switches and control mechanism and the apparatus involved in the establishment of a desired 120 conversational connection. Assume that the subscriber of line 100 desires to hold a conversation with a subscriber of line 217 located in the same office. Assume further that the code of the office designation of the local 125 office is represented by a certain abbreviation which in terms of dial impulses is represented by three digits. Assume also that the numerical designation of line 217 is represented by certain other digits. 130

The calling subscriber upon removing his receiver from the switchhook causes the operation of line switch 101, thereby extending the line 100 to an idle trunk 104. The initiation of the call also causes the operation of the sender selector 112 to select an idle sender such as 113 and 114. The calling subscriber now operates his dial to send the series of impulses representing the office code which are recorded on the office registers immediately followed by the impulses representing the digits of the called subscriber's line. The designations of the office and the called for subscriber's line represented by the operation of the calling dial are transferred, for example, to sender 113. Following this operation the sender connector 115 is operated for associating this sender with any one of a plurality of outgoing markers, such as 117 and 118. Following the operation of the outgoing marker and the transfer of the designations thereto, one of the district frame connectors 119 or 120 is selected for extending the connection to the district frame 108. Inasmuch as line 100 was extended to the district frame 108 upon the initiation of the call by the subscriber, the connection is now extended over line 122 to the incoming frame 200. The next step in the establishment of the connection is to connect the sender through the sender connector 208 to an idle incoming marker for controlling the selective operation of the incoming selector switches and the complete care of the desired connection. Before this operation, however, the outgoing marker has been released and is in readiness for use in the establishment of other desired connection. The designations recorded on the sender are now transferred to the selected incoming marker, for example 210, in turn causing the operation of the incoming frame connectors and the selection of the proper one of the final translators which serves the group of called lines containing the line wanted for this particular call. When the incoming marker is connected to the final translator the connector frames respond to the operation of the final translator for operating the vertical row of contacts associated with the line 217 extending to the called for subscriber. Following this operation the horizontal row of contacts in the incoming and connecting frames are operated for establishing the connection through from the calling subscriber to the called subscriber and in turn releasing any mechanism which is not required during the conversational period.

60 *An outgoing marker encounters trouble.*

In the establishment of conversational connections, both the outgoing marker and the incoming marker functioned normally and, therefore, completed their control over

the associated mechanism within the predetermined interval of time allotted for this purpose. The markers may, however, find it impossible to complete a connection due either to a fault within the marker itself or to a fault within the frames, frame or trunk connectors in the wiring involved in the progress of establishing a connection. In order to illustrate the manner in which the trouble indicator shown in Figs. 5 and 6 operates, it will next be assumed that the outgoing marker encounters trouble at any one of several of its different stages of operation. For this purpose it may be assumed that the connection being established is one which requires the use of both a district and an office selector switch.

At the instant the outgoing marker is seized by a sender through the sender connector, relay 450 operates as described in patents to W. W. Carpenter, Nos. 1,600,399 and 1,594,003, issued Sept. 21, 1926, and July 27, 1926, respectively. This relay initiates the operation of the time measuring device shown in Fig. 3, which counts an interval of time sufficient for the marker, if functioning normally, to control the district and office selector switches and to release in the regular manner. The time measuring device includes a series of counting relays 300, which operate successively under the control of the constantly driven interrupter 309. These relays apply ground potential at definite intervals of time to the various conductors leading to the distributing frame 307. By strapping conductor 319 to various ones of these conductors the time interval measured may be adjusted, as desired.

As soon following the operation of relay 450 as the interrupter 309 closes, relay 302 is operated in a circuit from ground through interrupter 309, conductor 320, outer left contact of relay 450, conductor 330, right contact of relay 308, conductor 321, right contact of relay 301 and winding of relay 302 to battery. Relay 302 operates and prepares a circuit from battery, through its winding, left winding of relay 301, contact of relay 302, back contact of relay 304, back contact of relay 306, conductor 322, and thence to ground at the right front contact of relay 450. When the interrupter 309 opens its contacts, its shunt is removed and relay 301 operates in series with relay 302. On the next closure of the interrupter 309, conductor 321 is extended through the right front contact of relay 301, right back contact of relay 303, winding of relay 304 to battery. Relay 304 operates and opens the circuit for relay 302, traced through its right winding and relay 302 releases. Relay 304 prepares a locking circuit through its own winding and left winding of relay 303, front contact of relay 304, thence to the grounded conductor 322,

as previously traced. On the next opening of the interrupter, relay 301 releases and the shunt being removed, relay 303 operates in series with relay 304.

5 On the next closure of the interrupter grounded conductor 321 is again extended to the winding of relay 302. This relay operates and prepares the circuit for relay 301, which operates the next time the interrupter opens. On the next closure of the interrupter the grounded conductor 321 is extended through the right front contacts of relays 301 and 303 and the right back contact of relay 305 to the winding of relay 10 306. The operation of relay 306 opens the holding circuit of relays 302 and 304, which thereupon release. Following this operation the interrupter opens and releases relays 301 and 303 and permits relay 305 to 15 operate in series with relay 306. Thus, the counting relays 300 are associated in different combinations under the control of the interrupter 309. From inspection it will be found that grounded potential is placed 20 on the various conductors leading to the distributor frame 307 at succeeding and definite intervals of time. With the distributing frame cross-connected as illustrated, relay 308 is operated as soon as the counting 25 relays 301, 303 and 305 are operated. The circuit for relay 308 may be traced from battery, through its winding, conductor 319, distributing frame 307, middle front contact of relay 301, 303 and 305, to the 30 grounded conductor 322.

If the marker encounters trouble relay 450 being operated, the interval of time is counted and relay 311 becomes energized in a circuit from battery through the winding 40 of relay 311, inner right contact of relay 310, right normal contact of slow-release relay 314, conductor 323, left contact of relay 308 to grounded conductor 322. Relay 311 operates slow-release relay 312, which in turn 45 operates the slow-release relay 313, which thereby operates the slow-release relay 314.

When relay 313 operates, it initiates the operation of the connecting device 400 for the purpose of connecting the marker to the 50 trouble indicator. The peg count register magnet 316 also operates the register to record of occurrence of the trouble.

In case the marker had progressed to a 55 point where it was associated either with the district or office switches the operation of certain relays as described in Patent No. 1,594,003, issued July 27, 1926, referred to above, would bring about the release in the manner explained in the referred 60 to application. The release of the marker would in turn cause the release of the operating relays of the time measuring device.

During the time the trouble indicator is 65 associated with the marker certain of the relays 501 to 536, inclusive, are operated to

record certain information regarding the apparatus involved and the point of progress which has been made up to the time when trouble was encountered. The manner of effecting the connection of the indicator relays 70 with the marker is fully described hereinafter. Relay 501 is operated in a circuit extending through the selected marker to the sender. Since relay 501 is individual to the particular sender illustrated, the indicator 75 operates to record the fact that this particular sender is the one involved in the establishment of the present connection. Had another sender, such as the sender represented by another relay, been the one 80 concerned, relay 502 in the indicator would have been operated. Relay 501 immediately locks through its right contact, over conductor 542 to ground, through key 580, conductor 685, armature and contact of relay 85 681.

The operation of relay 501 in addition to completing a circuit for causing the illumination of lamp 546 and the establishment 90 of its own locking circuit also conditions an energizing circuit for one of a series of code relays 600. These code relays function to cause the energization of the selecting magnets 601 to 605 of a receiving printer in various combinations whereby a 95 permanent record of the trouble encountered may be made. The printer is so arranged that the symbols designating the various mechanisms employed in the establishment 100 of a conversational connection as determined by the particular code relays operated appear in different columns. This particular arrangement makes it possible for an attendant to quickly ascertain by merely glancing 105 at the record sheet the apparatus involved in a particular connection and the point of progress made by the call when trouble was encountered.

A receiving printer especially adapted for 110 the purpose of recording the information relative to the occurrence of trouble is shown and described in pending application to Harry Pfannenstiehl, Serial No. 397,903, filed July 21, 1920. Inasmuch as the printer mechanism per se does not form a part of the 115 present invention only so much of the mechanism as is necessary for a clear and concise understanding of the invention has been illustrated. A general reference to the Harry Pfannenstiehl application is hereby made for an understanding of the manner in which the various parts of the present system so far as the printer mechanism and circuits are concerned operate and the details of operation whenever such arrangements and details are hereinafter mentioned but are not particularly illustrated or described.

The receiving printer illustrated comprises 120 the usual selecting magnets 601 to 605, 125 130 135

These selecting magnets operate in various combinations in accordance with the energization of the code relays 600 and serve to select in various combinations the associated 5 permutation bars through the medium of which one of a plurality of type bars 610 is selected for operation. The printing of the character in accordance with the selected type bar is effected through the operation 10 of power operated means, which supplies the necessary energy to throw the type bar into contact with the paper. As described in the Harry Pfannenstiehl application referred to above, the type bars 610 are arranged in a 15 movable basket or carriage 611. The carriage 611, together with the type bars 610, is moved relatively to the platen (not shown) through the rotation of a shaft 613. Secured to the carriage 611 and rotatable 20 with and slideable along the shaft 613 is a worm gear 614. This gear 614 engages the teeth in a rack 615.

As is the customary practice in receiving printers of this general type the carriage 25 611 is returned under the action of a retractile spring. When it is desired to restore the carriage to its left hand position the rack 615 is shifted so as to cause the disengagement of the teeth formed therein with 30 the teeth in the worm gear 614. Also mounted on the shaft 613 is a ratchet wheel 620 which is engaged by a pawl 621 operatively connected with an eccentric 623. The eccentric 623 is mounted on a shaft 624 to 35 which power is communicated from a rotating motor 625 through a friction clutch 626. The eccentric 623 is arranged with respect to the shaft 624 such that for each 40 rotation of this shaft the pawl 621 is operated for causing the rotation of the ratchet wheel 623 through a distance equal to the space of one tooth. In other words, the corresponding movement of the type carriage 45 611.

Also secured to the shaft 624 is a stop arm 630 normally in engagement with release latch or stop 631. When it is desired to release the shaft 624 for performing the printing and other necessary operations magnet 50 633 is energized for causing the movement of the toggle joint 632 and in consequence the movement of the stop 631 out of the path of the arm 630. There is also mounted on 55 the shaft 624 a cam 634 which closes contacts 635 once for each rotation. The function of these contacts will be described hereinafter.

Mounted on the carriage 611 is a brush 60 arm 640. This brush arm carries three equally spaced brushes 641, 642 and 643. The first two of these brushes are arranged to engage the segments of segmented rings 645 and 646, while the latter brush engages 65 the continuous ring 647. The segments of

the rings 645 and 646 are with the exception of certain ones of the segments connected to circuits extending to the front contacts of indicating relays 500.

The operation of the code relays 600 is dependent upon the operation of the indicator relays 500 and the position of the brush arm 640.

In the case of another trouble relay 512 is operated in a circuit from battery, through 75 its left winding, thence through the contacts of relays 401 individual to the particular marker that is in trouble. To this end relay 403 individual to the marker is operated in circuit from battery, through the right front 80 contact of relay 313, right contact of relay 314, key 324, conductor 325, upper winding of relay 403, right contact of relay 405, lower contact of relay 404 to ground. Relay 403 locks through its lower winding and 85 front contact, winding of relay 404 to ground which establishes an operating circuit for relay 404. The operation of relay 403 causes the operation of the multi-contact relay 401 in a circuit traceable from battery, 90 through the winding of relay 401, upper contact of relay 403 to ground at the upper contact of relay 404. Relay 401 operates and connects the various leads from the trouble indicator shown in Fig. 5, through 95 to the marker.

When relay 314 operates it opens the circuit of relay 311, which relay releases, in turn releasing relay 312, which likewise releases relay 313, thereby releasing relay 314. 100 Relays 312, 313 and 314, being slow to release, provide an appreciable interval of time for the apparatus to function. As soon as relay 313 releases, it removes battery from conductor 325, causing the release of 105 relay 401 and the disconnection of the trouble indicator from the marker.

Upon the release of relay 313 and while relay 314 is still operated, relay 310 is operated in a circuit from battery through its 110 winding, left contacts of relay 314 and 313 to ground. Relay 310 immediately locks through its inner left contacts, left contact of relay 308 to conductor 322. Relay 310 opens the circuit of relay 311 to prevent a 115 repetition of the operation. Relay 310 at its outer left contact closes a circuit to relay 317 and ground. Since relay 401 is individual to the particular marker which has encountered trouble, the operation of relay 120 512 records the identity of this particular marker. Had another marker been involved, such as the marker represented by relays 402, then relay 511 would have been operated. Relay 512 locks to the conductor 542. 125

Thus, it will be seen that the trouble indicator shown in Fig. 5 may be associated with any one of the several markers in response to the time measuring device associated with the marker, provided such marker 130

has encountered trouble at any of the various stages of its operation, dependent upon the particular point at which the trouble occurred. The indicator will give various 5 signs of information which are of assistance in determining the nature of the trouble and in locating the exact point in the system where it occurred. While only the important items have been taken into account in 10 the disclosure, it will be evident that the trouble indicator may be extended to secure an indication of various other operative conditions in the marker in order to enable the tracing of the trouble more minutely to the 15 exact point of its occurrence.

Inasmuch as the trouble indicator is common, as shown in Fig. 1, to all the outgoing markers, it may happen that at the time the particular marker finds trouble and attempts 20 to appropriate the indicator, said indicator is already engaged in a connection with another marker. The circuits are so arranged, however, that the connection of the indicator to the marker is prevented when 25 trouble occurs and the marker is released for service and the record of the occurrence of trouble therein is lost. The details of this particular part of the mechanism have been described quite fully in the applications referred 30 to above.

Selecting magnets 601, 602, 604 and 605 are operated over a circuit extending from grounded battery winding of the selecting magnets, armatures and contacts of relay 35 650, conductor 607 and the middle contact and armature of relay 404 to ground. The selecting magnets 601, 602, 604 and 605 being energized, the permutation bars of the printer are selected to cause the printer to 40 be shifted from the lower case to the upper case, or the position for printing numerals or other special characters. Simultaneously with the operation of the permutation bars contact 651 is closed, whereupon the energizing 45 circuit for start magnet 633 is completed. Shortly after relay 404 operates relay 650 operates over a circuit from grounded battery, winding of relay 650, conductor 607, and middle contact and armature of relay 404 to ground. Relay 650 in energizing 50 opens the energizing circuit for the selecting magnets 601, 602, 604 and 605, which caused the positioning of the selecting mechanism to effect the shift operation, and also 55 completes an energizing circuit for the circuit breaker 627. This circuit may be traced from grounded battery, winding of circuit breaker 627, conductor 628, middle armature and contact of relay 650, extreme 60 left hand armature and contact of relay 680 and conductor 607 to ground at the armature of relay 404. The circuit breaker 627 is energized for connecting the power circuit with the motor 625, which is thereupon caused to rotate and accordingly sup-

ply power to the shaft 624, through the friction clutch 626.

It should be noted that relay 650 is maintained energized so long as relay 404 is operated, the release of which will not occur 70 until the information pertaining to the apparatus involved in the establishment of the connection and the point of progress made by the call at the time trouble was encountered has been recorded by the printer. 75 Also, it is pointed out that the receiving printer described in the previously referred to application is constructed so that it remains in the shifted position until the selecting magnets 601 to 605 are operated for 80 performing the unshift operation.

The release magnet 633 having been energized upon the closure of contact 651 operates toggle joint 632 for releasing the arm 630 together with the shaft 624. The 85 shaft 624 rotates and the eccentric 623 causes the advancement of the carriage 611 through the ratchet wheel 620 to position the brush 641 on to segment 654. Provided relay 511 is operated upon engagement of 90 the brush 641 with segments 654, an energizing circuit is completed for code relay 655. The circuit for this relay may be traced from grounded battery, conductor 656, extreme right hand contact and armature of relay 611, conductor 570 and segment 654, brushes 641 and 643, ring 647, conductor 607 to ground at the armature and contact of relay 404. If relay 511 is operated at this time code relay 655 is energized over the circuit just traced, causing the energization of selecting magnets 601, 602, 603 and 605 in a manner such as to cause the printer to record the numeral 1 in column Number 1. This particular record 100 indicates that since column Number 1 is allotted to the markers the attempted connection involved marker Number 1. Should marker Number 2 have been involved in the connection, code relay 658 would be energized upon the engagement of the brush 641 with the segment 654 and accordingly numeral 2 would be recorded in the proper column. 110

Now as the carriage 611 is advanced step 115 by step from left to right, the brushes 641 and 642 successively connect the associated segments 660, 662, 663, 664 and 665 with the continuous ring 647, whereupon the code relays 600 are energized in accordance with 120 the energization of the relays of the indicating system 500.

Following the passage of the brush 642 off of segment 665 and the engagement of brush 641 with segment 666 an energizing circuit is established for relay 667 over a circuit extending from grounded battery, winding of relay 667, conductor 668, segment 666, brush 641, brush 643, ring 647, conductor 657, conductor 607 to ground at 130

the contact and armature of relay 404. Relay 667 closes through its contact circuits extending to the selecting magnet 601 to 605. The selecting magnets are accordingly 5 energized to cause the printer to assume the unshifted position. From this point on the recording operation characters such as letters, as distinguished from numerals, are recorded in the several columns.

10 For each rotation of the shaft 624 the carriage 611 is advanced so that one or the other of the brushes 641 or 642 is in engagement with the segments in the ring 645 and 646 for recording in the proper columns in 15 formation concerning the switches involved and the point of progress made in the establishment of a connection. When the carriage 611 nears the completion of its travel segment 670 is engaged by brush 641. The 20 bridging of this segment with continuous ring 647 through the respective brushes causes the energization of relay 673, over a circuit extending from grounded battery, winding of relay 673, conductor 672, segment 670, brushes 641 and 643, continuous ring 647, conductor 657, conductor 607 and the contact and armature of relay 404 to ground. Relay 673 in closing its contact causes the energization of selecting magnet 30 602, whereupon mechanism of the receiving printer is operated for causing the operation of the line feed mechanism to bring an unprinted area into printing position. In order to provide sufficient space between the 35 different lines of printing, segments 670 and 671 are connected together electrically so that a double spacing operation occurs through the engagement of the brushes 641 and 642 with the respective segments of the 40 ring 645 and 646. Immediately following the engagement of the brush 642 with segment 671, brush 641 engages segment 677. This segment as well as the remaining segments of the ring 645 and 646 are connected 45 to the winding of relay 675, which is energized upon the engagement of one or the other of the brushes 641 and 642 with the respective segments. Relay 675 in energizing closes the circuit including selecting magnet 604. This particular selecting magnet serves to cause the disengagement of the 50 rack 615 with the worm gear 614, whereupon the carriage 611 is returned to its left hand position. The purpose of having all the last 55 segments in the ring 645 and 646 connected together electrically to the winding of the relay 675, is to insure that the printer shall not get locked up by the brushes 641, 642 getting on a dead segment.

60 Relay 675 in energizing also causes the energization of relay 678 over a circuit extending from battery, winding of relay 678, right hand contact and armature of relay 675, back contact and armature of relay 679, 65 contacts 635, which are closed once for each rotation of the cam 634, conductor 683, conductor 607 and the contact and armature of relay 404 to ground. Relay 678 opens the circuit of start magnet 633, so that shaft 624 comes to rest at the end of the revolution in which it is started. Magnet 633 is deenergized before circuit breaker 627 operates to insure that shaft 624 shall always come to its normal position. Relay 678 is locked up over a circuit including the winding of relay 679. Relay 679 conditions an energizing circuit for relay 680, the energizing circuit of which is completed upon the next closure of contacts 635. Relay 680 is also locked up through its own armature 80 and contact. This relay also opens the circuit of the circuit breaker 627, which releases and disconnects the power circuit from the motor 625. Extending from the winding of relay 681, through the middle 85 contact and armature of relay 680 to the first segment in the ring 647 is a circuit for the relay 681, but which is not completed until the carriage 611 has returned to its left hand position. When in this position 90 the circuit for relay 681 is completed for removing the ground extending to the indicator relays 500. Thus, any of these relays which were previously operated would be released. The release of the relays may also be effected through the opening of a manual key 580. With the carriage 611 in its left hand position and the relays 500 deenergized as well as the multiple contact relay 401 released, the apparatus is in readiness for connection with the same or another marker involved in a later connection which has encountered trouble.

95 It should be noted that the back contacts of certain indicator relays are connected together electrically. Should any of the relays 500 fail to function properly code relay 684 will be energized which completes through its contacts energizing circuits for 100 selecting magnets 601, 602, 604 and 605. The energization of these selecting magnets with the printer in the upper case position causes the operation of the shift and a blank space in the record for that group of relays 105 thus indicating that the relay system 500 has operated incorrectly. In groups of relays not having such connections, a relay should operate for every record, and a failure of any code magnet to operate will be 110 indicated by a bar corresponding to no code magnet operated to make a period on the record and thus indicate trouble.

115 A sample record showing the apparatus involved in a connection and the point of progress made at the time trouble was encountered is illustrated in Fig. 7. The printing of the various designations appearing on the illustrated record will now be 120 described.

125 Assume first that the sheet upon which 130

the record is printed bears a number of columnar spaces, each of which has a definite and predetermined position on the sheet, and which bears certain designations representing the various mechanisms employed in the establishment of a conversational connection. Assume further that the sheet is arranged in the receiving printer in a manner to bring the designated columns in their proper position so that the record of the apparatus involved in a given connection will appear in the proper column. In other words, there is a column allotted to each particular operation of the system which is apt to encounter trouble and which is arranged so that designations will appear in the proper columns, according to the progress of the call. An examination of this sample record shows that column Number 1 is allotted to the markers, column 2 to the senders, column 3 to the district frame, etc. and with numeral designations in these columns or others and symbolic designations representing the apparatus employed in a given connection, the nature and source of the trouble can be quickly ascertained. Also the permanent record of the occurrence of trouble makes it possible to compare the records of other failures to determine whether it is the same apparatus causing trouble.

Now with the thus arranged record sheet properly inserted in the receiving printer, a record of any failures occurring in the operation of the apparatus will be automatically recorded. Assume now for the purpose of illustration that a call is desired to be completed and the office dialed is number 252 BLAck and that trouble is encountered in attempting to establish the desired connection. A record of the apparatus involved will be recorded on the sheet in the columns designating the respective mechanisms. In the record shown in Fig. 7 line 1 the translator check circuit of marker Number 2 failed. This fact is detected by the absence of a designation in a column allotted to this particular operation for the one labeled "Horizontal." From this record it is seen that the connection involved marker Number 2, sender Number 1, district frame Number 1. Since the failure occurred in the operation of the translator check circuit, no designation letter *x* appeared in the office frame column. The designation indicates that all the apparatus up to and including the relay designated at the top of the column has functioned correctly. This fact is shown by the appearance of all the code letters which shows that the selected office code relays of the marker failed to release.

Record Number 2, shows that the marker Number 2 failed to release when used in connection with sender Number 1 on a call to 252 BLAck, whose trunks are located on

a district frame Number 1. This particular trouble is indicated by the appearance of numerals and the *x*'s indicating that the conversational connection has been correctly set up, but the marker failed to release. The last three letters B D B in line Number 2 represents BLAck, the office code dialed in an arbitrary code. Had another marker or sender been involved in establishing the connection just described, other designations would appear in the columnar spaces allotted to these particular mechanisms. For the sake of brevity a further detailed description of the manner in which the various designations are recorded will not be described here, since the operation was fully discussed in connection with the operation of the indicating mechanism 500 and the code relays 600.

Record Number 3 shows that the marker Number 1 failed to release when used in connection with sender Number 2 to connect to an office whose trunks are located on a district frame, the numbered call being ACAdemy 222.

Record Number 4 shows that marker Number 1 failed to release, when used in connection with sender Number 2 to connect an office whose trunks are located on office frame Number 1. The number called is ENGlewood 364.

The record Number 5 is the same as record Number 4, except that sender Number 2 is used instead of sender Number 3. This record also indicates that the trouble lies in the marker Number 1 and not in any sender or connecting circuit. The dot in place of the office frame designation indicates a condition of trouble in the printer circuit or in the circuit between the trouble indicator relays 500 and the marker.

As the previous description was with reference to trouble encountered in the outgoing marker of the system, had the call progressed sufficiently far to involve an incoming marker, such as, for example, 210 of Fig. 2 and if the trouble occurred at this point in the connection trouble indicator 250 and recorder 251 would be associated in a manner similar to that described in connection with trouble in the outgoing marker. The apparatus associated with the incoming markers is identical to that common to the outgoing markers. Therefore, a similar record would be made of trouble encountered in this particular part of the system.

It will also be obvious that the trouble indicating mechanism may serve in connection with the markers, whether the call being handled is a local one or one involving inter-office trunks. For the purpose of brevity it is considered unnecessary to describe the operation incident to the establishment of an interoffice connection and the occurrence of trouble therein, but the functions of the

marker and associated apparatus in handling such connections are fundamentally the same.

What is claimed is:

5. 1. In combination, a plurality of selectively operable switches for establishing various connections, means operated in accordance with failures in the operation of said switches, circuit connections controlled 10 by said means, a page recording mechanism for recording information giving a designation of the switches involved in a connection, and mechanical means for successively associating groups of said circuit connections with the recording mechanism so that the same group will invariably cause the printing of the record in the same position. 15
2. The combination in a telephone system of switching apparatus for extending 20 connections, a switch controlling mechanism for governing the operation of said apparatus, a recording device, and mechanically operated means for associating said device with said mechanism if it should fail to 25 function properly for causing the operation of said device to produce a permanent record giving information of the different degrees of progress made by such mechanism. 30
3. The combination in a telephone system of switching apparatus for extending 35 connections, a switch controlling mechanism for governing the operation of said apparatus, a control device, means for connecting said device with said mechanism if said mechanism fails to function properly, a recording device, and mechanical means operative to associate said recording device with said control device for effecting the 40 operation of the recording device to produce a permanent record giving information of the different degrees of progress made by such mechanism. 45
4. The combination in a telephone system of switching apparatus for extending 50 connections, a switch controlling mechanism for governing the operation of said apparatus, a control device, means for connecting said device with said mechanism if said mechanism fails to function properly, a recording device comprising selecting and recording mechanisms, and means integral with said recording mechanism for controlling the association of said selecting mechanism with said control device to cause the 55 recording of information concerning the apparatus involved in a connection and the point of progress of such connection. 60
5. The combination in a telephone system of switching apparatus for extending 65 connections, a switch controlling mechanism for governing the operation of said apparatus, a control device, means for connecting said device with said mechanism if said mechanism fails to function properly, a recording device, and means integral with
- said recording device for controlling its operation according to the operation of said control device to record in different columnar spaces information concerning the apparatus involved in a connection and the 70 point of progress made at the time of failure. 75
6. The combination in a telephone system of switching apparatus for extending connections, a switch controlling mechanism for governing the operation of said apparatus, a control device, means for connecting said device with said mechanism if said mechanism fails to function properly, a recording device, and a commutator device for associating said recording device with said control device to effect the operation of the recording device to record in a permanent form information concerning the progress of the apparatus involved in a connection. 80
7. The combination in a telephone system of switching apparatus for extending connections, a switch controlling mechanism for governing the operation of said apparatus, a control device, means for connecting said device with said mechanism if said mechanism fails to function properly, a recording device, and a commutator device effective in accordance with the operation of the recording device for successively associating the different parts of said control device with said recording device which responds to record designations in different columns concerning the progress and the apparatus involved in a connection. 85
8. The combination in a telephone system of switching apparatus for extending 90 connections, a switch controlling mechanism for governing the operation of said apparatus, a control device, means for connecting said device with said mechanism if said mechanism fails to function properly, a recording device, and a commutator device advanced step by step on each operation of the recording device for associating the recording device with the control device for effecting the operation of the former device to record in different designated columns information concerning the progress and the apparatus involved in a connection. 100
9. The combination in a telephone exchange system of switching apparatus for extending connections, a switch controlling mechanism for governing the operation of said apparatus, a control device, means responsive to the failure of said mechanism to function properly to connect said control device to said mechanism, a recording device, means for supplying energy to said device, means operated immediately when said mechanism fails to function properly for rendering said energy supplying means effective, and means controlled by said recording device for associating it with said control device to record the apparatus in- 105
- 110
- 115
- 120
- 125
- 130

volved in a connection and the point of progress made at the time of failure.

10. The combination in a telephone exchange system of switching apparatus for extending connections, a switch controlling mechanism for governing the operation of said apparatus, a control device, means responsive to the failure of said mechanism to function properly to connect said control device to said mechanism, a recording device, means for supplying energy to said device, means operated immediately when said mechanism fails to function properly for rendering said energy supplying means effective, means controlled by said recording device for associating it with said control device to record the apparatus involved in a connection and the point of progress made at the time of failure, and means responsive to the recording operation to disconnect the energy supplying means from said recording device.

11. The combination in a telephone system of selective switches for extending connections, a controlling mechanism associable with said switches for governing their operation, a device including a plurality of relays operated in accordance with the various degrees of progress of the connection, switching means for associating said relays with said mechanism upon the occurrence of trouble therein, a plurality of code relays controlled by said device for setting up predetermined circuits, mechanical means for successively completing the circuits extending to said relays as determined by the relays of said device, and means operated by said code relays for producing a permanent record of information giving the apparatus involved and the point of progress made at the time trouble was encountered.
12. The combination in a telephone system of selective switches for extending connections, a controlling mechanism associable with said switches for governing their operation, a device including a plurality of relays operated in accordance with the various degrees of progress of the connection

switching means for associating said relays with said mechanism upon the occurrence 50 of trouble therein, a plurality of code relays controlled by said device for setting up predetermined circuits, a commutating device for successively completing the circuits extending to said relays as determined by 55 the relays of said device, and means operated by said code relays for producing a permanent record of information giving the apparatus involved and the point of progress 60 made at the time trouble was encountered.

13. In combination, a plurality of selectively operable switches for establishing various connections, means operated in accordance with failures in the operation of said switches, circuit connections controlled by said means, a recording mechanism having a movable carriage for recording information giving a designation of the switches involved in a connection, and means integral 70 with said carriage for successively associating groups of said circuit connections with the recording mechanism so that the same group will invariably cause the printing of the record in the same position. 75

14. The combination in a telephone system of switching apparatus for extending connections, a switch controlling mechanism for governing the operation of said apparatus, a control device, means for connecting said device with said mechanism if said mechanism fails to function properly, a recording device comprising a selecting mechanism and a recording mechanism having a movable carriage, and means integral with 85 said carriage for controlling the association of said selecting mechanism with said control device to cause the recording of information concerning the apparatus involved in a connection and the point of progress of 90 such connection.

In witness whereof, I hereunto subscribe my name this 19th day of November, A. D., 1924.

LOUIS M. POTTS.
